UNITED STATES PATENT OFFICE.

PHILIP A. BECKER, OF BROOKLYN, NEW YORK.

SUPPLEMENTAL BOX-LID.

1,244,163.

Specification of Letters Patent. Patented Oct. 23, 1917.

Application filed October 11, 1915. Serial No. 55,222.

To all whom it may concern:

Be it known that I, PHILIP A. BECKER, a citizen of the United States, and a resident of New York, borough of Brooklyn, county of Kings, and State of New York, have invented a certain new and useful Improvement in Supplemental Box-Lids, of which the following is a full, clear, and exact specification.

10 This invention relates to a class of devices adapted to be used in conjunction with boxes.

My invention has for its object primarily to provide a supplemental lid whereby a substantially rectangular plate of glass having three of its edges free of a frame, or rim may be applied on the open top of the body of a box for permitting merchandise in the box to be displayed without exposure 20 to the air as well as preventing the collecting of dust and the like, and which is of a form so that the lid may be swung to open and closed positions to allow the merchandise to be conveniently dispensed from 25 the box as occasion requires. The invention consists essentially of a transparent plate which is preferably substantially rectangular in shape for being movably disposed on the open top of the body of a box, 30 and parts of the transverse edges of the plate adjacent to one of its longitudinal edges are formed to provide retaining portions so that a rim of metal, or the like may be anchored on this longitudinal edge 35 to obviate the requirement for inclosing all the edges of the plate in a frame which tends to obscure portions of the contents of the box from view as is incident to many forms of display lids of this class in ordinary 40 use.

Another object of the invention is to provide means on the rim whereby the plate may be detachably applied to the lid of the box so as to be swung to open and closed 45 positions on the body of the box when the lid is moved accordingly; and a further object of the invention is to provide a supplemental lid of a simple and efficient construction.

50 A practical embodiment of the invention is represented in the accompanying drawing forming a part of this specification in which similar characters of reference indicate corresponding parts in all the views, the said 55 invention being more fully described here-

inafter, and then pointed out in the claims at the end of the description.

In the drawing, Figure 1 is a perspective view, partly broken away, showing one form of supplemental box lid embodying 60 my invention.

Fig. 2 is a fragmentary top view of the transparent plate with the form of rim applied thereon as shown in Fig. 1.

Fig. 3 is a section taken on the line V—V 65 of Fig. 4, and

Fig. 4 is a fragmentary perspective view of a slightly modified form of the box lid.

The supplemental box lid has a transparent plate 10 which is preferably of glass 70 as well as being preferably substantially rectangular in shape, and this plate may be of any size so as to be movably disposed on the open top of the body, as 11, of a box having a lid, as 12, hinged thereto, or when 75 the supplemental lid is used in conjunction with cigar boxes the plate 10 may be of a size to movably fit between the usual extending upper edges of the side walls thereof, as shown in Fig. 1. 80

As it is well known that glass is the most advantageous material for the transparent plates employed in this class of supplemental box lids, and owing to the difficulty of causing metal to be fixed thereto against 85 accidental displacement, I provide on the transverse plate retaining portions, as 13 and 14. As illustrated in Figs. 1, 2, 4, the retaining portions 13 and 14 may be provided by notching two of the opposite corners of the transparent plate, as at 15, in the forms of acute angles. 90

On the longitudinal edge of the transparent plate which is provided with the retaining portions 13 and 14 is a metal rim 18. 95 The metal rim 18, may be in the form of a strip 19 somewhat longer than this edge of the plate, and the ends of this strip are turned over the inclined edges of the angular notches 15 so as to overlap the under-side of the plate. Thus by providing the retaining portions 13 and 14 metallic rims 100 may be anchored to the transparent plate against accidental displacement.

Serving as means to permit the transparent plate with its metallic rim to be detachably applied to the lid of the box so as to be swung to open and closed positions on the open top of the body of the box when the lid 12 of the box is moved accordingly, 110

on the rim may be provided an upwardly projecting panel, or strip 26 which is adapted to be disposed across the lower part of the box lid, and this panel is slightly longer than the lid of the box. On the ends of the panel 26 may be provided any suitable forms of sleeves, or clamps, for instance the types of sleeves, as shown at 27 and 27^a in Fig. 1, or forms of bent wire sleeves, as shown at 28 Fig. 4, may be used. The sleeves are of sizes as well as being sufficiently spaced apart so as to be removably fitted over the side edges of the box lid; and instead of these forms of sleeves any other desired means may be employed for detachably connecting the transparent plate with its rim to the box, therefore, I do not claim as part of my present invention the particular types of sleeves herein illustrated.

20 To apply the supplemental lid to a box for use, it is disposed so that the sleeves may be slidably moved over the side edges of the box lid to permit the transparent plate to be positioned for closing the open top of 25 the body of the box. When the box lid is then swung rearwardly, the transparent plate will be guided to an open position for allowing the contents of the box to be dispensed, or, when the box lid is reversely moved the transparent plate will be guided to a closed position on the body of the box so that the contents of the box may be displayed without exposure to the air as well as preventing the collection of dust and the like thereon.

In the foregoing description, I have embodied the preferred form of my invention, but I do not wish to be understood as limiting myself thereto, as I am aware that 40 modifications may be made therein without departing from the principle, or sacrificing any of the advantages of this invention, therefore I reserve to myself the right to make such changes as fairly fall within the 45 scope thereof.

Having thus described my invention, I claim as new and desire to secure by Letters Patent:

1. In a supplemental lid of the character described, a substantially rectangular glass

plate having two of its opposite corners notched to provide two retaining portions whereby a rim may be anchored on one of the edges of the plate to permit the plate to be connected to a box or the like so as to be 55 swung to open and closed positions thereon as well as permitting three of the edges of the plate to be free of a rim.

2. In a supplemental box lid, a substantially rectangular glass plate adapted to be 60 movably disposed on the open top of the body of the box, the said plate having two of its opposite corners notched to provide two retaining portions, and a metallic rim anchored on the retaining portions of the plate to permit the plate to be connected to the box so as to be swung to open and closed positions thereon as well as permitting 65 three of the edges of the plate to be free of a rim.

3. In a supplemental box lid, a rectangular glass plate adapted to be disposed on the open top of the body of a box, the said plate having two of its opposite corners notched to provide two retaining portions, a metallic rim on the retaining portions, and means on the rim whereby the plate may be detachably connected to the box lid so that the plate may be swung to open and closed positions on the body of the box when the 80 box lid is moved accordingly.

4. In a supplemental box lid, a plate adapted to be disposed on the open top of the body of the box, the said plate having a notched portion at each of two adjacent 85 corners to provide two oppositely arranged retaining portions, a rim adapted to fit over the edge of said plate adjacent the notched portions thereof, together with means connected to said rim adapted to positively engage the said notched retaining portions, and means on the said rim whereby the plate may be detachably and hingedly connected to the box lid.

This specification signed and witnessed 95
this ninth day of October A. D. 1915,

PHILIP A. BECKER.
